STOVE WITH BAFFLE

Harold O. Berry and Theodore W. Kappler,
Gardner, Mass., assignors to Florence Stove
Co., Gardner, Mass., a corporation of Massa-
chusetts

Application January 10, 1939, Serial No. 250,106

7 Claims. (Cl. 126—44)

This invention relates to stoves.

This invention is more particularly concerned with stoves utilizing oil burners of one type or another, especially the type known as range oil burners which are well known in the art.

In certain forms of home-cooking stoves there is provided an oven which is heated by hot gases circulated thereabout. One particular type of stove is that in which range oil burners have been introduced in the firebox in place of a coal or wood fire. In this type there is over the firebox a stove top against which the heat from the burners impinges directly. Alongside of the firebox is the oven with flues so arranged that heat from the burners may travel laterally over the top of the oven, downwardly around the end and finally out through a flue to the chimney.

In the course of the operation of a stove of this type it is essential that there be flues to permit the entrance of sufficient air for proper combustion of the burner, and in the ordinary case the flues are of such size that more air enters the stove than is essential for proper combustion. As the hot gases rise from the burner they ordinarily carry with them a considerable quantity of adjacent air which is at a much lower temperature, with the result that the mixture of gases that pass about the oven is at a lower temperature than would be the case if the cooler air surrounding the burners could be excluded.

One of the objects of the invention, therefore, is to provide a stove construction whereby, in a stove using range oil burners, the hot gases that ascend to impinge against the stove top and to subsequently pass about the oven will be of a higher than ordinary temperature.

Another object of the invention is to provide a stove construction that will be simple, cheap and easy to assemble, that will minimize the amount of cold air that may mix with the hot gaseous products of combustion.

Another object of the invention is to provide a stove construction having all of the foregoing attributes but which will not interfere with easy cleaning, adjustment or repair of the oil burners.

Another object of the invention is to provide means whereby the effective temperature of the gases from the burners may be controlled by varying the amount of cold air that may pass upwardly by the burners to mix with the heated products of combustion.

These and other objects of the invention will become apparent as the description of a preferred form of my invention proceeds with the aid of the accompanying drawings in which

Fig. 1 is a perspective view of a stove broken away in part showing the burners and improved baffle construction;

Fig. 2 is a vertical section on the line 2—2 of Fig. 1;

Fig. 3 is a vertical fragmentary section on the line 3—3 of Fig. 1.

Referring to Fig. 1 which shows essential elements of the invention with the outer parts of the stove broken away, there is a stove casing 2 having a stove top 4, firebox 6, and oven 8.

In the firebox, as shown in Figs. 1 and 2, are mounted in any convenient fashion the range oil burners 10 of which there may be one or more. In the ordinary case it is customary to use two 15 burners as they provide sufficient heat for a stove of ordinary proportions. The oil supply connections are not shown as they constitute no part of this invention.

It will be noted that the oil burners are positioned directly under the stove top 4 and that there is a flue passage 12 which extends over the top of oven 8.

At some convenient position in the firebox are provided the necessary air entrance ports which may be positioned in a removable side door which will fill the door frame 14 indicated in Figs. 1 and 2. For convenience the door and the flues have not been shown. However, it is understood that means is provided for the admission of air 30 to the firebox in order that combustion of the oil burners may be supported.

From the description thus far it will be apparent that, in the absence of restraining means, the air surrounding the burners will be drawn 35 upwardly by the ascending hot gases from the burners to mix with those gases as they pass laterally through flue 12. This, of course, would reduce the average temperature of the gases, with the result that the oven temperature would be 40 correspondingly lower.

By the invention, however, we contemplate controlling the amount of cold air which may mix with the hot gases, and this is done by the provision of a baffle 16 which is shown in its relationship to the stove and the burners in Figs. 1, 2 and 3. The baffle comprises one or more members of metal or other material suitable for the purpose and which may take the forms illustrated. The baffles 16 have apertures there- 50 through somewhat larger than the diameter of the oil burners positioned therebelow. The baffles may be supported in any convenient manner, and in the case shown, the flanges 18, which extend longitudinally of the baffles from the front to the 55

5 rear of the stove, rest on the lip 28 of the stove side wall and the top edge 24 of the oven. The arrangement is such that the baffle, if in one piece, will be a proper distance from the burners, 10 or if in a plurality of parts as shown, will be sufficiently close so that a separate removable member may be supported thereby which will be adapted to control the effective area between the top of the burners and the baffle through 15 which ascending cold air must pass. It has been found in practice that good results are obtained when the distance between the outer circumference of the burner and the lower edge of the baffle is about three-quarters of an inch.

15 In the construction shown, we have used a separate member in the form of a short truncated cone 26 having a radially extending flange 28 which rests on the edge of the hole through baffle 16.

20 Member 26 may have its vertical dimension as desired to vary the effective space 30 between the lower edge and the burner 10. Furthermore, member 26 is removable so that the burner 10 may be readily removed through the larger hole 25 of baffle 16 which is in excess of the diameter of the outer shell of the burner.

As indicated, the baffle itself may be readily removed for cleaning, by virtue of the construction shown in which flange 18 merely rests on 30 supports 20 and 24 and is not permanently secured thereto. However, if desired, the baffle 16 could be built in as an integral part of the stove with the members 26 remaining removable.

It is believed apparent that in the operation of 35 a stove of the form shown the average temperature of the gas passing through the flue passage 12 will be considerably higher than would be the case were baffle 16 not utilized. The air necessary for the combustion of the oil burners enters 40 the burner through the perforations in the burner shells so that combustion is substantially complete by the time the gases have passed from the burners. Therefore, the amount of cold air passing upwardly outside the burners may be 45 minimized as much as desired without affecting the efficiency of combustion. The result of this baffle construction is that the average temperature of the gases impinging on stove top 4 and passing through the flue passage 12 will be increased, thus improving the efficiency and 50 performance of the stove.

Because of the increased efficiency, the burners may be operated at a lower oil setting, or if operated at the same setting as heretofore, the 55 heat available for cooking will be greater, with a corresponding saving in time.

By supplying a set of truncated cone members 26 of different heights, the air passage 30 may be varied to secure different results, depending 60 on the performance desired. But regardless of the particular member 26 used, the ease with which oil burner 10 may be cleaned or adjusted will in no way be impaired as all of the members 26 will be readily removable.

65 While we have shown and described a preferred form of our invention, we wish it to be distinctly understood that we do not intend to be limited thereby, but only by the appended claims.

70 We claim:

1. A baffle for use in a stove of the type described comprising a metal member having as many openings therethrough as there may be burners in said stove, means on the edges of said 75 baffle for engagement with suitable supporting

means on said stove, said openings being larger than said burners, and a removable depending flange positioned in each opening, each said flange being in the form of a short tube and having an annular rim at its upper portion for engagement with that part of said baffle forming the circumference of said hole. 5

2. A stove of the class described having an oven and a cooking top, a passage about said oven, a firebox, a plurality of burners in said firebox, said firebox being connected with the passage about said oven, a plurality of baffle sections in said firebox of the same number as there are burners, said baffles dividing the firebox into upper and lower parts and being positioned generally at the top of said burners, each of said baffle sections having an opening therethrough directly above each of said burners, the effective area between said baffle sections and burners being relatively small whereby the amount of low 20 temperature air from the lower part of said firebox that may pass into the upper part of said firebox to mingle with products of combustion of said burner may be definitely limited, each baffle section adapted to be carried by suitable supports in said stove and adjacent ends of said baffle sections constructed to engage each other to form a relatively gas-tight joint. 15

3. A stove of the class described, having an oven and a cooking top, a passage about said oven, a firebox, a burner in said firebox, said firebox being connected with the passage about said oven, a baffle in said firebox dividing the latter into upper and lower parts and positioned generally at the top of said burner but spaced therefrom, said baffle having an opening therethrough directly above said burner, said opening being sufficiently larger than said burner to permit easy access to and removability of the latter, said baffle having a removable depending circular 40 flange positioned in said baffle opening, the lower edge of said flange being in close proximity to the circumference of said burner to form a relatively small effective area between said baffle and burner whereby the amount of low temperature 45 air from the lower part of said firebox that may pass into the upper part of said firebox to mingle with products of combustion of said burner may be definitely limited. 5

4. The construction as set forth in claim 3, in 50 which the baffle comprises a generally horizontal metal member, supporting means for said baffle on said stove and said oven, and said flange being in the form of a truncated cone. 5

5. A stove of the class described, having an oven and a cooking top, a passage about said oven, a firebox, a perforated shell type burner in said firebox, said firebox being connected with the passage about said oven, a baffle in said firebox dividing the latter into upper and lower parts 60 and positioned generally at the top of said burner and spaced therefrom, said baffle having an opening therethrough directly above said burner, the minimum diameter of said opening being sufficiently larger than said burner to permit access to and removability of the latter, the edge of the baffle forming the circumferential boundary of said opening being in close proximity to the circumference of said burner to form a relatively small effective area between said baffle 65 and burner whereby the amount of low temperature air from the lower part of said firebox that may pass into the upper part of said firebox to mingle with products of combustion of said burner may be definitely limited. 70

6. A stove of the class described, having an oven and a cooking top, a passage about said oven, a firebox, a burner in said firebox, said firebox being connected with the passage about said oven, a baffle in said firebox dividing the latter into upper and lower parts and positioned generally at the top of said burner but spaced therefrom, said baffle having an opening therethrough directly above said burner and a flange depending therefrom, the interior diameter of said flange being sufficiently larger than said burner to permit access to and removability of the latter, the lower edge of said flange being in close proximity to the circumference of said burner to form a relatively small effective area between said baffle and burner whereby the amount of low temperature air from the lower part of said firebox that may pass into the upper part of said firebox to

mingle with products of combustion of said burner may be definitely limited.

7. A baffle for use in a stove of the type described and utilizing a perforated shell type burner, comprising a metal member having as many openings therethrough as there may be burners in said stove, the edges of said baffle adapted for engagement with suitable supporting means on said stove, each said opening being bounded by a flange depending from said baffle, each said flange being in the form of a short inverted conical-shaped tube having an internal diameter great enough to permit access to and removal therethrough of the burner thereunder without disturbing the position of said baffle. 15
